GARDENING TOOL HEADPIECE

Arthur Fath, Blue Ash, Ohio

Application September 18, 1952, Serial No. 21,517

Term of patent 14 years

(Cl. D35—2)

To all whom it may concern:

Be it known that I, Arthur Fath, a citizen of the United States of America, residing at Blue Ash, in the county of Hamilton and State of Ohio, have invented a new, original, and ornamental Design for a Gardening Tool Headpiece, of which the following is the specification, reference being had to the accompanying drawings, forming a part hereof, and wherein:

Figure 1 is a plan view of a gardening tool headpiece showing my new design.

Figure 2 is a side elevation.

Figure 3 is a front elevation.

Figure 4 is a perspective view.

The characteristic feature of my design resides in the angular configuration of the head piece

band when viewed in side and end elevation, as seen in Figs. 2 and 3 of the drawings.

I claim:

The ornamental design for a gardening tool headpiece, substantially as shown and described.

ARTHUR FATH.
